(57) **CLAIM**

The ornamental design for a connector socket, as shown and described.

DESCRIPTION

FIG. 1 is a top perspective view of a connector socket showing my new design.

FIG. 2 is a bottom perspective view thereof.

FIG. 3 is a side elevation view thereof.

FIG. 4 is an another side elevation view thereof.

FIG. 5 is a top elevation view thereof; and,

FIG. 6 is a bottom elevation view thereof.

The broken line portion of the figure drawings is included to show unclaimed subject matter only and forms no part of the claimed design.
